UNITED STATES PATENT OFFICE.

VICTOR NELSON PERRY, OF BATAVIA, NEW YORK.

PNEUMATIC STACKER.

1,133,060.

Specification of Letters Patent. Patented Mar. 23, 1915.

Application filed April 11, 1914. Serial No. 831,163.

To all whom it may concern:

Be it known that I, VICTOR N. PERRY, a citizen of the United States, and a resident of Batavia, in the county of Genesee and State of New York, have invented a new and useful Improvement in Pneumatic Stackers, of which the following is a specification.

My invention is an improvement in pneumatic stackers, and has for its object to provide a fan for use in pneumatic stackers, so arranged that the straw may be delivered axially of the fan directly to the blades or vanes, wherein the central portion of the fan is free and unobstructed to receive the straw, and wherein a double blade construction is provided, the two portions of the blade being arranged one behind the other, the front portion being the straw blade and the rear portion the air blade.

In the drawings: Figure 1 is a side view of a portion of a threshing machine provided with the improved stacker, the stacker being in section, Figs. 2 and 3 are sections on the lines 2—2 and 3—3, respectively, of Fig. 1, looking in the direction of the arrows, and Fig. 4 is a perspective view of one of the blades or vanes.

The present embodiment of the invention is shown in connection with a thresher 1, and the fan casing 2 of cylindrical form for the stacker is provided with an axial inlet 3 and with a tangential outlet 4. The outer end is connected with the usual discharge tube 5, and the opposite face of the casing 2 from the inlet has a central opening through which the fan hub and its shaft project.

The fan comprises a circular plate or disk 7, and a ring 13, which are connected by blades or vanes, to be described, and the plate or disk 7 is secured to the hub 6 of the fan, by means of bolts 6^a, and the opening 3^a of the fan casing through which the shaft and the hub extends is large enough to prevent any engagement of the hub with the fan casing 1.

The fan shaft 9 is journaled in suitable bearings 11, on a bracket arm 12, extending rearwardly from the frame of the thresher, and the hub is rigidly connected with the shaft by means of a key 10. A pulley 14 is secured to the shaft at the opposite side of

the bracket from the fan, and the pulley is adapted for engagement by a belt or the like to connect the shaft 9 with a moving part of the thresher, whereby to rotate the shaft 9 and the fan connected therewith.

The fan is constituted by the disk 7, the ring 13 and four blades or vanes which are arranged between the ring and the disk and connect the ring to the disk. Each of the blades or vanes consists of two portions 14 and 14^a, arranged at an acute angle with respect to each other and connected by an arched or curved portion 15, the said portions 14—14^a—15 being integral. The portions 14 and 14^a are curved radially with respect to the fan, in the same direction, and the portion 14^a is of greater length than the portion 14. A trough 16 is provided for carrying the straw from the thresher to the fan, the said trough passing through the inlet 3 and through the opening of the ring 13, and delivering to the blades or vanes.

The straw from the thresher is carried by the trough 16, and delivered to the fan, being deposited directly upon the blades. Each blade or vane is thus double and the sheet of material from which each blade or vane is formed is provided at each side edge with an angular flange 17, and each flange is provided with openings 18, for receiving rivets 19 or the like to connect the flanges to the disk 7 and the ring 13.

The rivets pass through the openings 18 and through registering openings in the disk and ring, and the said blades or vanes thus connect the ring to the disk. The arched portion 15 of each blade or vane is at the inner edge of the ring 13, and between the portions of each blade the said ring is provided with a series of openings 20.

The openings 20 provide for the inlet of air to the space between the portions of the blade. The flanges 17 of the blades it will be noticed, are between the portions 14 and 14^a, so that they do not obstruct the departure of the straw from the fan. Because of the fact that the straw is deposited directly on the blades or vanes the edges of the blades or vanes do not strike the straw to break up the same, and since the vanes are supported at each side throughout their en-

tire length, a very strong, rigid construction results.

When a fan blade breaks, it as a rule, will pierce the fan casing and in addition to throwing the fan out of balance will generally cause considerable damage. With the improved construction breakage is reduced to a minimum, and in addition the blast delivered by the fan is much heavier.

10 When the straw leaves the trough 16, it passes through the large central opening of the ring 13, into a position directly upon the blades of the fan. The suction created by the blades together with the centrifugal 15 force causes the straw to be forced outwardly through the tangential outlet 4 of the casing.

When the outlet of the fan casing is reached, the straw leaves the fan and is 20 thrown directly upward, the blades assisting the air current in this operation. The portion 14 of each blade or vane is the straw blade, while the portion 14^a is the air blade. When the straw blade reaches the outlet of the 25 casing, a strong upward motion is imparted to the straw by the blade, and this motion is assisted by the current of air from the rear or air blade. Since there is no central spider and no shaft at the center of the fan there 30 is nothing to cause winding of the straw and consequent friction, so that less power is required to operate the improved fan than with the ordinary fan.

The straw cannot hang over or become 35 twisted around the fan blade, nor will it be whipped to pieces by the blades nor dragged along against the sides of the fan casing. Hence a large amount of friction found in the ordinary fan is eliminated. When the 40 straw leaves the fan casing, it receives not only the impetus of the straw portion 14, but also receives the blast from the portion immediately following.

I claim:—

45 1. A device of the character specified, comprising a cylindrical fan casing having an axial inlet and a tangential outlet, and a fan within the casing, the casing having at the end remote from the inlet a central opening, a stub shaft journaled adjacent to the casing and extending into the opening, a hub keyed to the stub shaft in the opening, a disk secured to the hub coaxial with the shaft, said disk being adjacent to the end of the casing, a ring at the opposite end of the casing, and a series of blades or vanes arranged between the ring and the disk and connecting the ring to the disk, and a trough 50 delivering to the fan and extending into the casing through the axial inlet and the opening of the ring, each of the blades or vanes comprising a sheet of material having at each side edge a flange, the flanges extending in the same direction and being secured to 55 the disk and the ring, said sheet being dou-

bled upon itself to form two portions radial to the disk and ring and the flanges being between the said portions and the ring having a series of openings between the portions of each blade, the connection between the said portions being at the inner surface of the ring, and each portion being arched radially of the fan in the same direction, the forward portion of each blade being approximately radial to the flange and the rear portion of each blade being inclined at an acute angle to the rearward portion.

2. A device of the character specified, comprising a cylindrical fan casing having an axial inlet and a tangential outlet, and a fan within the casing, the casing having at the end remote from the inlet a central opening, a stub shaft journaled adjacent to the casing and extending into the opening, a hub keyed to the stub shaft in the opening, a disk secured to the hub coaxial with the shaft, said disk being adjacent to the end of the casing, a ring at the opposite end of the casing, and a series of blades or vanes arranged between the ring and the disk and connecting the ring to the disk, each of the said blades or vanes consisting of two portions converging toward the center of the fan, the connection between the two portions being at the inner edge of the ring, the ring having a series of openings between the portions of each blade, the forward portion of each flange being approximately radial to the fan, and the two portions being arched in the same direction and having their convex faces forwardly.

3. A device of the character specified, comprising a fan casing having an axial inlet in one end and a tangential outlet, and a fan arranged within the casing, said fan comprising a disk and a ring arranged coaxial and with the ring adjacent to the inlet and a series of blades connecting the ring to the disk, each blade or vane consisting of two portions connected at the inner edge of the ring and diverging toward the periphery of the ring, a stub shaft at the end of the casing remote from the inlet to which the disk is secured, and a trough extending through the inlet and the opening of the ring, the portions of all of the blades being arched radially of the fan and in the same direction and arranged with their convex faces forwardly, the forward portion of each blade or vane being approximately radial to the fan, and the ring having openings between the portions of each blade.

4. In a device of the character specified, a fan comprising a disk and a ring arranged in parallel spaced relation and coaxial with each other and a series of blades or vanes connecting the disk and the ring, each blade or vane consisting of two portions connected at the inner edge of the ring and diverging toward the periphery of the ring,

the ring having openings between the portions of each blade.

5. A fan comprising a series of blades arranged in spaced relation, each blade consisting of two portions converging toward the center of the fan, and a disk and a ring arranged co-axial on opposite sides of the

blades and connected to the blades for holding them in spaced relation, the disk having openings between the portions of each blade. 10
